UNITED STATES PATENT OFFICE.

PIERRE E. GIROUX, OF JOHNSTOWN, NEW YORK.

DESIGN FOR A SLIPPER.

55,602.

Specification for Design.

Patented July 6, 1920.

Application filed January 3, 1920. Serial No. 349,339. Term of patent 7 years.

To all whom it may concern:

Be it known that I, PIERRE E. GIROUX, a citizen of the United States, residing at Johnstown, in the county of Fulton and State of New York, have invented a new, original, and ornamental Design for Slippers, of which the following is a specification, reference being had to the accompanying drawing, forming a part hereof.

The figures are respectively, a top plan view and a perspective view, showing my new design.

I claim:

The ornamental design for a slipper, as shown.

PIERRE E. GIROUX.
